UNITED STATES PATENT OFFICE.

MATTHEW A. FORD, OF ROCKFORD, ILLINOIS.

GRIDIRON.

1,345,590.

Specification of Letters Patent.

Patented July 6, 1920.

Application filed February 10, 1920. Serial No. 357,583.

To all whom it may concern:

Be it known that I, MATTHEW A. Ford, a citizen of the United States, residing at Rockford, in the county of Winnebago and State of Illinois, have invented certain new and useful Improvements in Gridirons, of which the following is a specification.

This invention pertains to gridirons, especially of the class adapted for out-door use for broiling over an open fire as when camping or outing.

The primary object is to provide a gridiron of generally improved construction and which shall be collapsible so that it will occupy but little space during transit. In this regard I have aimed to provide a casing which houses the gridiron in collapsed form and which serves as a handle for supporting the gridiron in use.

And the object is to provide a gridiron the grid elements of which are constructed in a simple and novel manner to permit ready collapsibility and to enable production at a comparatively low cost.

Still another object is to provide a gridiron of either the single or double grid type, in the former of which the grid is supported by legs upon the ground and in the latter the double grids are held by a handle.

Other objects and attendant advantages will be appreciated as the invention becomes better understood by reference to the following description when considered in connection with the accompanying drawing in which—

Figure 1 is a perspective view of a pair of grids in disassociated relation embodying my improvements;

Fig. 2 is a side view on a reduced scale of a gridiron constructed according to my improvements;

Fig. 3, a detailed perspective view of one of the longitudinally tapered bars employed in each grid;

Fig. 4, a detailed perspective view of the pivoted end of one of the said tapered bars;

Fig. 5, a side view of a grid, collapsed; and

Fig. 6, a perspective view of the casing with the gridiron in collapsed condition therein.

As mentioned above, my invention contemplates the provision of a gridiron of such novel construction as to permit of its

being collapsed into a very compact bundle and placed in a small casing for purpose of transportation. This casing serves the additional function of a handle for supporting the gridiron when in use.

The gridiron is composed generally stated of two grids, or grid plates, practically identical in construction.

Hence, a detailed description of one will suffice. Each grid plate is composed of a pair of longitudinally tapered bars 7, in the present instance preferably formed of sheet metal pressed to channel shape and tapered in the manner shown plainly in Fig. 3. To

one end of each bar 7 is pivotally attached at 8 an end portion 9 of a channel shape similar in dimensions to the adjacent end of the bar 7. Upon these bars 7 is mounted a plurality of cross bars 10 each of which is

slidable lengthwise of and upon the tapered bars to and from an operative position. 70

The end crossbar 11 on each pivoted end portion 9 is fixed with regard thereto against a sliding movement and thus serves as an end abutment to prevent displacement of the cross bars from this end of the tapered bar portions 9. The crossbars 10 are

slidable upon the tapered bars toward the narrow end thereof to a compact position such as illustrated in Fig. 5 in which all of

the crossbars are disposed entirely upon the pivoted end portions 9. This permits the tapered bars 7 to be swung inwardly upon the pivots 8 to a compact position in parallel relation to the bars 10, as shown plainly

in Fig. 5. To open up a grid plate the bars 7 are swung out into parallel relation, and, holding the cross bars 11 uppermost, the remaining bars 10 are dropped to positions limited by the size of their respective openings 12 in engagement with the tapered bars 7. 90

The openings 12 in the different crossbars are graduated in size, those farthest from the bar 11 being the largest in size so that the crossbars will be permitted to slide only a limited distance toward the 95 larger ends of the tapered bar 7 thus spacing the crossbars evenly as shown in Fig. 1.

Suitable means is now provided for holding the grids in spaced relation and for permitting convenient detachment of one grid from another and also for permitting attachment of the grids at different distances apart for reasons which will be presently

obvious. This is done in the present instance by means of spacer elements or legs 13 which are pivotally attached at 14 to the outer extremities 15 and 16 of the tapered bars 7 and ends 9 respectively of only one of the grids. Each spacer element has a plurality of slots 16 for the reception of T-shaped ends 17 on the ends of tapered bars of the other grid. In use, assuming that 10 one of the grids is suitably supported the upper grid will be associated with the lower one by suitable connection of the ends 17 in the slots 16 for holding the meat or other foodstuffs firmly between the grids.

15 I have now aimed to provide a handle for supporting the grids and which will also serve as a casing for housing them when not in use. This casing is preferably of a telescopic construction comprising parts 18 and 19. As shown in Fig. 6, part 18 is attached to slide into and out of part 19, the latter being rectangular in cross section and the former being preferably open along one side as at 20 to permit quick and easy reception 25 of the collapsed grids. The grids when collapsed in the manner shown in Fig. 5 are of such dimensions that they may be disposed side by side in the casing section 18, and it will be obvious that this section may be inserted telescopingly in section 19 and thus completely housed therein. When the grids are ready for use, the casing section 18 may be connected to a bar of the intermediate crossbars 10 of the lower grid in the 30 manner shown in Figs. 1 and 2, that is, the narrow end of the casing section 18 is shaped to fittingly engage over the ends of the crossbars 10 in such manner as to effect a substantial supporting connection between 35 these parts. When the casing, section 18 is so associated with the lower grid, the other section 19 may be fitted on to the outer end of the section 18, in the manner shown in Fig. 2 thus providing an effective and substantial handle for supporting and holding 40 the grids in use. It will be obvious from the foregoing that gridirons of this character are adapted for holding a steak or any meat or other foodstuffs over an open fire 45 for broiling, also that the gridiron may be very quickly disassembled and folded into a very compact relation in the casing.

50 In the event that only one of the grids is to be used as a stationary gridiron to be supported over a fire from the ground the legs 13 will serve for supporting this grid. It will, of course, be understood that these legs may be of any suitable length, or if desired, extensions may be provided so that 55 the grid may be supported at the proper elevations above the fire, or if desired, a separate grid of the construction described above, that is, collapsible, might be provided with suitable supporting legs, and thus 60 serve as an independent grid to be sup-

ported over the fire from the ground, as distinguished from being held by means of a handle.

It is believed that the foregoing conveys a clear understanding of the principle and objects of my invention, and while I have illustrated and described but a single practical embodiment thereof, it should be understood that various changes might be made in the construction and arrangement without departing from the spirit and scope of the invention as expressed in the appended claims, in which—

I claim:

1. The combination of a pair of collapsible grids and a sectional telescopic receptacle shaped to receive and house the grids in collapsed form and to serve as a handle for the grids when in operative form. 80

2. The combination of a gridiron the bars of which are collapsible into compact relation and a casing shaped to receive and inclose the collapsed gridiron and to constitute a handle therefor when in operable form. 85

3. A gridiron comprising a pair of longitudinally tapered bars in parallel spaced relation, a plurality of cross bars slidable lengthwise of and upon said tapered bars from a closely related position at one end thereof to spaced positions limited by the taper of the bars, and legs for supporting the bars in a horizontally disposed position. 90

4. A gridiron comprising a pair of sectional longitudinally tapered bars articulated adjacent to one end, a plurality of cross bars slidable lengthwise of and upon said bars and being held in spaced relation by the taper thereof, said cross bars being slidable onto said end sections and the tapered sections of the bars being foldable into close relation to the cross bars. 100

5. A gridiron comprising a pair of sectional longitudinally tapered bars having pivoted end sections; cross bars slidable lengthwise of and upon said tapered bars and held in spaced relation by the taper thereof, said cross bars being movable onto said pivoted ends whereupon the tapered bar sections may be folded into close relation to the cross bars, and legs attached to the corner portions of the gridiron. 110

6. A gridiron comprising, in combination, a pair of collapsible grids including cross bars movable from compact parallel relation to open, spaced relation and a casing shaped to receive the grids in collapsed relation and to detachably engage certain of the cross bars when in open relation for supporting the grids. 120

7. A gridiron comprising a pair of grids each adapted to be collapsed, means for securing the grids in spaced relation, and a casing for housing the grids when collapsed and shaped to detachably connect to one of 130

the grids for supporting them in operative relation.

8. A gridiron, including a pair of longitudinally tapered bars, an end section pivoted to each bar, cross bars slidable lengthwise of and upon the tapered bars from spaced positions limited by the taper thereof to a compact position on said end sections, whereupon said tapered bars may

be folded into close relation to the cross 10 bars.

9. The combination of a pair of collapsible grids, and a casing for housing the grids when in collapsed form and constituting a handle for supporting the grids in operative 15 form.

MATTHEW A. FORD.
